SAMUEL H. CAMP, OF JACKSON, MICHIGAN

COMBINATION GARMENT AND SUPPORT

Application filed November 26, 1929. Serial No. 409,776.

This invention relates to combination garments consisting of an inner belt or support surrounded by an external garment which furnishes a smooth exterior over the inner belt and in addition makes a form fitting garment that gives the proper shape to the body when the exterior garments are worn.

An object of the invention is to produce an outer garment giving smoothness of contour to the body while permitting belt adjustments to furnish abdominal support.

Another object of the invention is to produce a combination garment in which the inner belt or support is adjustable by means of lacings at the side of the garment and the outer garment is adjustable at the side over these lacings through the flexibility furnished by rubber woven or elastic cloth.

Other objects will appear in the following description, reference being had to the drawings, in which:

Fig. 1 is an inside view of the combination garment in fully open position.

Fig. 2 is an outside view of the inner belt or support disengaged from the outer garment for purpose of illustration.

Fig. 3 is a view of the combination garment in position on the wearer with the outer garment open to better show the operation of the inner belt.

Fig. 4 is a view of the combination garment in operating position on the body of the wearer.

Fig. 5 is a view of the buckle or clasp in the tensioning arrangement.

Referring to Fig. 1, the outer garment may be considered for purpose of description, as divided into a back member 1, a front member 2, and two side portions 3 and 4. The back member 1 has two double stays of bone or metal, 5 and 6, extending clear across the garment to give it proper rigidity. In addition there are two double stays 7, 8, extending from the bottom of the outer garment to approximately the waist line at 9, 10. The absence of the stays in the upper portion of the seams 11 and 12 gives proper freedom to the movement of the chest and arms of the wearer while the lower stayed portions 7 and 8 furnish the strength and rigidity necessary

to give the desired uplift through the inner belt or support.

The outer garment has a pair of buttons 12' in the back member and a pair 13 in the front member on which may be buttoned shoulder straps 14, 15, to hold the outer portion of the garment in position on the wearer.

The front member has a series of hooks 16 at one side adapted to fasten in the eyes 17 on the side portion 4. The side portions 3 and 4 have elastic or rubber cloth 17', 18 extending from the bottom of the outer garment substantially to the waist line. It is preferable also to place an elastic gusset 19 in the front portion.

It is immaterial what cloth is used to make the outer garment, but for pleasing appearance, the entire outer garment with the exception of the elastic portions and the upper front portion 20, may be made of brocaded cloth. The upper portion 20 of the front member may be made of ribbed mercerized or silk cloth.

The inner belt or support consists of two rear sections 21, 22, sewed into the seams containing short stays 7 and 8, respectively. These sections extend from the waist line to the hip portion of the garment. To the rear sections 21, 22 are adapted to be laced side sections 23 and 24 respectively. Side section 24 is integral with front member 25 of the belt and the other side section 23 is adapted to be removably secured to the front member by means of hooks 26 and eyes 27.

The front member 25 preferably has three pairs of stays 27', 28 and 29. The front member also carries two tensioning straps 30, 31. The strap 31 is separable from the end portion 32 to permit the belt to be attached and detached from the body. The joint between the straps 31 and 32 may be a hook and eye arrangement 33. The straps 30 and 32 pass over bar 34 on the buckle in Fig. 5 and then under the front bar 35. The tab members 36' and 37 are fastened to the bar 36 of the buckle or clasp and have eyelets through which pass the adjusting laces 37', 38. These laces may be threaded through the eyelets of tab member 36 and eyelets of the belt sections, for example, like that described in

my copending application Case #1, filed October 30, 1929, Serial No. 403,384.

The outer garment may have garter straps 39, 40, 41 and 42 attached to the sides of the front and rear members respectively and the inner belt may have two garter straps 43, 44, attached to the sides of the front section 25.

In adjusting the garment to the wearer the combination is placed across the back and hooks 26 are clasped in the eyes 27 to place the belt or support around the waist. The wearer will then grasp the ends of straps 30 and 32 and pull toward the front. This puts appropriate tension on the tab members 36 and 37 which draws the laces through the eyelets between sections 22 and 24 and 21 and 23. By pulling on these straps the belt is tightly drawn around the body and on account of the location of the ends of the straps at the lower portion of the front member 25 there is an uplift on the lower abdomen to assist in keeping the organs in position, as will be clearly seen by inspecting the final position of the adjustment in Fig. 3. The ends of the straps after the adjustment is finally made are passed under keepers 45, 46. In fact, the adjustment may be made with the straps in this position.

It will be understood that the construction of the clasp in Fig. 5 is such that a pull on the strap ends will force the slide 34 slightly to the rear and thus permit the strap to freely pass through the clasp, but when tension is relieved in the strap member the resisting force of the laces forces the bar 35 into firm engagement with the slide bar 34. This causes the strap to be gripped tightly and the position held. The outer garment is then fastened around the body by grasping the section 2 (see Fig. 3), causing the hooks 16 to engage the eyelet 17. When the outer garment is clasped in position it will have the appearance shown in Fig. 4. This figure illustrates the relation between the adjustable feature of the inner belt, namely laces 37, 38, and the resilient members 17, 18, on the outer garment. The eyelets in the tab member and belt section permit slight automatic adjustment of the laces as the body moves and this adjustment occurs at the same place as the adjustment of the elastic in the outer garment.

Having described my invention, what I claim is:

1. A combination garment consisting of a front and a back member, long stays in the center of said back member extending thereacross, short stays at the side of the back member extending from the bottom to the waist line of the garment, rear belt sections joined to the back member adjacent the short stays, a front belt member having two parts joined by quick attaching means, buckles at each side of the front belt member, lacing passing

from the front belt member through said rear belt sections and connected to said buckles, a tensioning strap attached to the lower part of the front belt member and passing through said buckles and elastic side sections passing over the lacings and joining the front and back members together whereby the inner and outer garments have their adjustable regions superimposed.

2. A combination garment consisting of a front and back member, long stays in the center of said back member extending thereacross, short stays at the side of the back member extending from the bottom to the waist line of the garment, a rear belt section attached inside each back member and having its upper end adjacent the upper end of the short stays, a front belt member, a side section permanently attached to said front belt member, another side section removably attached to the said front belt member by hook and eye clasps, lacing tabs, lacing passing through the rear and side belt sections and engaging said lacing tabs, a tensioning strap attached to the lower part of the front belt section and extending upwardly to engage a lacing tab on one side of the garment, a strap anchor attached to the lower front portion of the front belt member and a tensioning strap removably attached to said anchor and extending upwardly to engage a lacing tab on the other side of the garment.

3. A combination garment consisting of a separable front member and a back member joined thereto by elastic fabric at the sides, rear belt sections having long side edges, eyeleted short side edges and bottom edges slanting upwardly from the long side edges to the short side edges, a separable front belt section having eyeleted side edges of substantially the same length as the short side edges of said rear belt sections, tensioning straps attached to the lower part of the front belt section, buckles through which said tensioning straps pass, lacings passing through the eyelets of said side sections and engaging said buckles, the long side edges of said rear belt section being attached to the inside of said back member with the upper end adjacent the waist line and the lower end below the hip crest line whereby tension placed on said straps draws said eyeleted edges together and places tension on the front belt section and on the back member from the waist line to points below the hip crest line.

In testimony whereof, I have signed my name to this specification this 18th day of November, 1929.

SAMUEL H. CAMP.
